UNITED STATES PATENT OFFICE.

IRVING J. BALL, OF BROCK, NEBRASKA.

CATTLE-GUARD FOR RAILROADS.

No. 823,498.

Specification of Letters Patent.

Patented June 19, 1906.

Application filed November 7, 1905. Serial No. 236,235.

To all whom it may concern:

Be it known that I, IRVING J. BALL, a citizen of the United States, residing at Brock, in the county of Nemaha and State of Nebraska, have invented a new and useful Cattle-Guard for Railroads, of which the following is a specification.

This invention relates to cattle-guards for railroads to be used at crossings to prevent horses, cattle, and other animals from passing onto the right of way; and it has for its object to improve and simplify the construction and operation of this class of devices.

With these and other ends in view, which will readily appear as the nature of the invention is better understood, the same consists in the improved construction and novel arrangement and combination of parts, which will be hereinafter fully described, and particularly pointed out in the claims.

In the accompanying drawings has been illustrated a simple and preferred form of the invention, it being, however, understood that no limitation is necessarily made to the precise structural details therein exhibited, but that the right is reserved to any changes, alterations, and modifications to which recourse may be had within the scope of the invention and without departing from the spirit or sacrificing the efficiency of the same.

In said drawings, Figure 1 is a top plan view of a cattle-guard constructed in accordance with the principles of the invention, showing the same applied in position for operation and a portion having been removed for the purpose of exposing the subjacent construction. Fig. 2 is an end elevation. Fig. 3 is a sectional view of one of the supporting-ties, showing one of the shaft-supporting spikes driven into the same.

Corresponding parts in the several figures are indicated throughout by similar characters of reference.

A main supporting-shaft 1 is supported beneath the rails 2 and transversely to the latter in eyes or transverse perforations 3, formed in spikes 4, a suitable number of which are driven in a tie or cross-timber 5, which latter has been shown as being approximately square in cross-section and set on edge, as clearly seen in Fig. 2 of the drawings, the upper edge being trimmed at the points where it supports the rails. Upon the shaft 1 are fulcrumed a plurality of pairs of levers L, each including an arm 6, depending from the shaft, an arm 7, extending obliquely from

the lower end of the arm 6 in an inward direction or toward the crossing, an arm 8, diverging from the arm 7 outwardly in the direction of the railroad, and a brace 9 connecting the arms 6 and 7 and serving to strengthen the structure. The arms 7 and 8 of the levers terminate in bracket-plates 10, all of which are disposed approximately in the same horizontal plane, which is approximately coincident with the horizontal plane of the heads of the rails, and upon these bracket-plates are supported guard-plates 11, one of said plates being connected with each pair of levers. Where there is only a single track, as shown in the drawings, three sets of levers and three guard-plates are required, one set being disposed between the rails and one set adjacent to each of the rails. If there is more than one track, it is obvious that additional sets of levers and guard-plates will be required.

A cross-beam 5' is disposed adjacent the cross-beam 5, and into said cross-beam are driven spikes 4, having apertured heads 3, supporting a shaft 12. The spikes 4 are in every respect like those used to support the shaft 1 and, as well as the latter supporting-spikes, are provided with enlargements 13 upon the heads thereof to enable them to be conveniently driven into position. The shaft 12 supports a plurality of pairs of levers 14, the inner ends of which are extended downwardly and connected pivotally with links 15, the opposite ends of which are connected pivotally with the lower ends of the levers L. The outer ends of the levers 14 are normally disposed in the horizontal plane of the flanges of the rails 2, and securely connected with said levers are gates G, which latter are preferably constructed of strap-iron of suitable dimensions, the straps being set on edge and suitably connected with each other so as to form meshes or openings of any desired dimensions. These gates are obviously adapted to swing upon the shaft 12 to an approximately vertical position, as shown in dotted lines in Fig. 2, and the upper or outer portions of the gates are preferably provided with barbs 16 of any suitable construction to deter animals from pushing against them when the gates are elevated.

The guard plates or platforms 11 may be constructed of cast-iron or other suitable material, and they may be provided with openings 17 for the purpose of decreasing the weight and also to admit of proper drainage.

Said plates or platforms are also provided with upstanding barbs 18, which will prevent animals from standing thereon.

Cross-beams 5^a are disposed adjacent to the inner sides of the cross-beams 5, the upper inclined sides of said cross-beams serving to support the platforms 11 when the latter have been depressed to a certain extent.

It will be seen from the foregoing description that when the inner free ends of the platforms or plates 11 are depressed the levers L will swing to the position indicated in dotted lines in Fig. 2, thus pushing the links 15 and the free ends of the levers 14 in an outward direction, thus lifting the gates to the approximately vertical position indicated in dotted lines in Fig. 2. It is obvious that when the platforms are thus depressed by an animal stepping thereon the gate, by swinging upwardly in front of the animal, will bar the further progress of the animal, which will also be rendered uncomfortable by the presence of the barbs upon the platforms and upon the gates, so that it will speedily turn, thus permitting the parts of the guard to resume their normal position.

Having thus described the invention, what is claimed is—

1. In a cattle-guard, a barbed platform supported for movement in a vertical arc, a supporting-shaft, a supporting-timber, and spikes engaging said timber and having perforated heads supporting the shaft.

2. In a cattle-guard, a supporting-timber, a plate or platform movable in a vertical arc, and a lever pivotally connected with the supporting-timber and having divergent arms terminating in bracket members supporting said plate or platform.

3. In a cattle-guard, a lever having a depending arm and divergent platform-supporting arms, a gate-supporting lever, and a link connecting the gate-supporting lever with the depending arm of the platform-supporting lever.

4. In a cattle-guard, a lever having divergent platform-supporting arms, and a supporting-timber disposed between said platform-supporting arms.

5. In a cattle-guard, a supporting-lever having divergent arms, a platform supported upon said arms, and a supporting-timber extending between said arms and platform to engage and support the latter when depressed.

6. In a cattle-guard, levers having depending arms and divergent platform-supporting arms, auxiliary levers supported at a distance from the platform-supporting levers, a gate member connected rigidly with the auxiliary levers, and connecting means between the gate-carrying levers and the platform-supporting levers whereby pressure upon the free inner end of the platform shall serve to elevate the free outer end or edge of the gate.

7. A platform supported to move in a vertical arc, a gate supported to move in a vertical arc, supporting means for the platform including divergent arms, a timber disposed between said platform and divergent arms to limit the downward movement of the platform, supporting means for the gate, and connections between the supporting means, the platform and the gate whereby downward pressure upon the free end of the platform will serve to elevate the free end of the gate.

8. A lever supported to swing in a vertical plane and having divergent arms, a platform supported upon said arms, and a timber supported between said arms and platform, said timber being tilted to present a flat side to support the platform when the latter is depressed.

In testimony that I claim the foregoing as my own I have hereto affixed my signature in the presence of two witnesses.

IRVING J. BALL.
